UNITED STATES PATENT OFFICE

172,067

YARN HOLDER OR SIMILAR ARTICLE

Herman L. Toelke, San Francisco, Calif.

Application October 12, 1953, Serial No. 27,156

Term of patent 14 years

(Cl. D3—19)

To all whom it may concern:

Be it known that I, Herman L. Toelke, a citizen of the United States of America, residing in the city and county of San Francisco and State of California, have invented a new, original, and ornamental Design for a Yarn Holder or Similar Article, of which the following is a specification, reference being had to the accompanying drawing, forming part thereof.

I claim:

The ornamental design for a yarn holder or similar article, as shown.
